Henry Ruppel,
A. S. Patterson

Attorney

UNITED STATES PATENT OFFICE.

HENRY RUPPEL, OF CLEVELAND, OHIO, ASSIGNOR TO AMERICAN STOVE COMPANY,
OF ST. LOUIS, MISSOURI, A CORPORATION OF NEW JERSEY.

BLUE-FLAME OIL-BURNER.

1,396,594.

Specification of Letters Patent.

Patented Nov. 8, 1921.

Application filed July 7, 1920. Serial No. 394,451.

To all whom it may concern:

- Be it known that I, HENRY RUPPEL, a citizen of the United States, residing at Cleveland, in the county of Cuyahoga and State of Ohio, have invented certain new and useful Improvements in Blue-Flame Oil-Burners, of which the following is a specification, reference being had therein to the accompanying drawing.
- 10 This invention relates to improvements in blue flame oil burners, and is of that type which has been known in the art for a great many years as the "wickless" blue flame oil burner, in which there is a trough in which 15 the oil is fed, the trough containing an initial lighting member.

The invention also pertains to that type of wickless blue flame oil burner in which the trough is vertically adjustable for controlling the level of the oil in the trough. This has also been known to the art for a great many years.

One object of my invention is to provide an improved sliding connection through 25 the medium of which the trough is raised and lowered, whereby a free movement is provided while at the same time a practically oil-tight sliding connection is accomplished.

30 Another object of my invention is the provision of a housing for the sliding connection which is provided with a closed bottom to receive any slight leakage that may possibly occur from wear of the parts, and 35 in which housing the leakage is vaporized by the heat conducted from the burner to the housing, the vapor passing up through the housing into the combustion chamber.

A further object of my invention is to 40 utilize the connection housing and a yoke loosely engaging the connection for raising and lowering the sliding connection and thereby the trough.

45 Further objects of my invention will appear from the following description and disclosure.

In the accompanying drawings:

Figure 1 is a side elevation of my burner shown in connection with a part of a frame 50 and a maintained level oil feed, the latter shown in vertical section.

Fig. 2 is an enlarged central sectional view of my improved burner.

Fig. 3 is a side elevation of my burner, the

sliding connection, housing and part of the 55 oil-feed pipe shown in vertical section. In carrying out my invention, I utilize any desired form of burner supporting frame 1, at the bottom of which is a suitable oil-feeding pipe 2. This oil feeding 60 pipe 2 communicates with a pipe 3, which in turn communicates with a well-known form of maintained oil level feeding device A. Since the construction and principle of operation of this oil-level feeding device A, has 65 been well-known in the art for many years, it is unnecessary to give any detail construction thereof.

My improvement utilizes the well-known annular trough B, which contains also the 70 well-known initial lighting or starting member C. Detachably seated on the upper end of the trough B, is the well-known perforated combustion section D, which is surrounded by the well-known hood E, for protecting 75 the combustion section from air drafts. As the foregoing elements of a blue-flame oil burner are well-known in the art, it is unnecessary to give any detail construction of them.

80 In carrying out my improvement, I provide a member F which extends transverse the trough B and is located below the trough. The ends 4 of this member F are suitably shaped to receive the bottom of the trough, 85 and the ends 4 and the trough are suitably connected, preferably by brazing or soldering. This member F, at one side of its center is solid, as at 5, and the other side is tubular, as at 6. This tubular portion 6 communicates at its outer end with the bottom 90 of the trough B, through an opening 7. An elongated sleeve 8, which is preferably integral with the member F, projects downward therefrom and is in communication 95 with the inner end of the tubular portion 6. A tube 9 projects upward from the member F, and has its upper open end 10 substantially in the horizontal plane of the upper end of the trough. An elongated tube 100 11 has its lower end 12 connected in any suitable manner with the oil feeding pipe 2, and extends upward into the elongated depending sleeve 8. The vertical passage 12' into which this elongated tube 11 slides, has its 105 upper end 13 contracted and the upper end of the passage 12' is tapered as at 14, to receive the corresponding tapered end 15 of

the elongated tube 11. The exterior surface of the tube 11 and the passage 12' have a machined fit so that practically an oil fit is made between them while at the same time the sleeve 8 can freely move vertically on the tube 11. The tapered portions 14 and 15 of the passage 12' and the upper end of the tube 11 form a valve seat for a purpose to be explained.

10 The lower end of the sleeve 8 has external screw-threads 16, to receive an internally screw-threaded stuffing box 17.

A housing G has its closed bottom 18 fastened in any suitable manner to the lower end of the tube 11. This housing projects upward and incloses the tube 11 and sleeve 8, and its upper end 19 is slightly enlarged and projects substantially to the level of the top of the trough B, when the latter is 20 in its lowered position, as shown in Fig. 2. This housing G has oppositely disposed vertical slots 20, and the ends of the member F have laterally projecting lugs which extend into these slots and move therein as 25 the trough is raised and lowered. This construction prevents any turning movement of the trough.

A collar 22 surrounds and loosely fits into an annular groove 23 formed in a sleeve 8. 30 The lower wall of the groove 23 is formed by an internally screw-threaded collar a, fitting a screw-thread 16 of the sleeve 8. This collar a is therefore adjustable in relation to the loose collar 22, and is held in its 35 adjustment by a suitable screw b passing therethrough to engage the screw-threads 16. This collar 22 carries two laterally projecting rods 24 and 25 which project through oppositely disposed inclined slots 26 and 27, 40 formed in the housing G. These rods 24 and 25 are smaller in diameter than the width of the slots 26 and 27, so that rollers 28 may be placed on the rods for engaging the upper and lower walls 26' and 27' of the 45 slots 26 and 27. The rod 24 projects beyond the housing G, as shown and receives a suitable handle 29.

By pushing the handle laterally the rods and their rollers will travel in the inclined 50 slots 26 and 27 and through the medium of the collar 22 and sleeve 8, cause the trough to be raised or lowered according to the direction in which the handle 29 is moved.

A slot 30 is formed in the housing G 55 above its lower end through which a suitable wrench may be passed for adjusting the stuffing box 17, and the wall of the housing G, is also provided with a plurality of openings 31 above its bottom.

60 In operation when the trough B is in its lowered position, the oil in the trough will be of a height corresponding to the oil level of the oil-level feeding device A, as will be readily understood, and at its greatest depth 65 in the trough. With the trough in this po-

sition, the burner is burning full flame and the tapered portions 14 and 15 form, in effect, a valve seat, thus relieving the passage 12' and the stuffing box 17 of any oil pressure. Owing to the elongated machined 70 bearing surfaces of the sleeve 8 and the tube 11, a practical oil sliding connection is formed, but should there be any seeping of oil from this sliding connection when the burner is standing unlighted or otherwise, 75 it will be collected in the bottom of the housing G, and when the burner is lighted and becomes heated, heat is conducted from the burner trough to the housing G, and the oil seepage will be vaporized in the housing and the air drawn through the openings 80 31, slots 30, 26, 27 and 20 causes an upward draft carrying the vapor into the combustion chamber above where it is consumed. Air reaches the interior of the combustion 85 section through the above-mentioned openings and slots and the housing in addition to serving the functions already described, and it further serves to cause a feed of air which is distributed and protected from external air drafts.

Owing to the open end 10 of the upwardly extending tube 9 and the large passages 6 and 7, the oil quickly flows from the trough when it is elevated and quickly flows into the 95 trough, when it is lowered. Attention is directed to the fact that the tube 9 is in a line with the tube 11, so that a wire can be readily passed through the tubes 9 and 11 to the large oil feeding pipe 2, for the purpose 100 of dislodging any collected sediment or other foreign matter which might interfere with a free flow of the oil to and from the burner trough B.

By providing the trough with a depending 105 tubular sleeve 8 and extending a tube 11 from the oil-feeding pipe 2, I provide an elongated bearing for the sliding connection whereby practically an oil-tight joint is formed with but little friction. The stuffing 110 box 17 is not essential in this construction, but is used primarily as a safety device should the sliding connection be subjected to some unnatural condition or use.

Having thus described my invention, what 115 I claim and desire to secure by Letters Patent is:—

1. In a burner of the type described, a vertically movable trough, an inwardly extending member at its bottom communicating with the trough, the said inward member having an elongated depending sleeve, an oil feeding pipe, a tube extending from the oil feeding pipe and fitting within the sleeve, the adjacent surfaces of the sleeve 120 and tube being machine finished, for the purpose described.

2. In a burner of the type described, a vertically movable trough, a centrally arranged depending elongated sleeve having 130

its upper end in communication with the trough, an oil feeding pipe, an upwardly extending elongated tube having its lower end connected with the oil-pipe and extending into the sleeve, the sleeve and tube having elongated bearing surfaces, for the purpose described, the lower end of the sleeve carrying a stuffing box surrounding the said upwardly extending tube, and means for

10 moving the trough up and down.

3. In a burner of the type described, a vertically movable trough, an inwardly extending member in communication with the trough, said member having an elongated 15 depending sleeve in communication with said member, the inwardly extending member having an upwardly extending tube with an open end, an oil-feeding pipe and an elongated tube extending from the oil feeding pipe into the sleeve, and means for moving the trough vertically.

4. In a burner of the type described, a vertically movable trough having at its bottom an inwardly extending member in communication with the trough, said member having an elongated depending sleeve in communication therewith, an oil feeding pipe, an upwardly extending elongated tube passing into the sleeve, the upper ends of 30 the sleeve and tube having a valve-seat connection when the trough is lowered for the purpose described.

5. In a burner of the type described, a vertically movable trough, having at its bottom an inwardly extending member in communication therewith, said member having a depending elongated sleeve, an upwardly extending stationary elongated tube passing into the sleeve, the tube and sleeve having 40 machined engaging surfaces, for the purpose described.

6. In a burner of the type described, a vertically movable trough, an oil feeding passage having a vertically slideable connec-

tion with the trough and in communication therewith, a housing depending from the trough and inclosing the sliding connection, the housing having a closed bottom and openings above its bottom, for the purpose described.

7. In a burner of the type described, a vertically movable trough having a depending slideable oil-feeding connection, a vertically arranged housing inclosing the oil feeding connection and having a closed bottom, the housing having oppositely disposed inclined slots, a collar surrounding the sliding connection, the collar having laterally extending rods passing through the slots, one of the rods extended and carrying a handle whereby the trough can be raised and lowered by turning the collar.

8. In a burner of the type described, a vertically movable trough having a vertically slideable oil-feeding connection in communication with the trough, a vertically arranged housing inclosing the slideable connection, the housing having oppositely arranged inclined slots, a collar loosely surrounding the slideable connection, the collar having laterally extending rods passing into the inclined slots, the upper end of the housing having vertically arranged slots and the trough laterally extending lugs in the slots, and means for rotating the collar for raising and lowering the trough.

9. In a burner of the type described, a vertically movable trough and oil-feeding passage having a vertically slideable connection with the trough and in communication therewith, a housing below the trough and inclosing the sliding connection, the housing having a bottom adapted to receive leakage from the sliding connection and air openings.

In testimony whereof I hereunto affix my signature.

HENRY RUPPEL.
